UNITED STATES PATENT OFFICE.

CHARLES JOSEPH RHODES, OF WAKEFIELD, ENGLAND.

MACHINE FOR FLANGING AND SEAMING SHEET-METAL RECEPTACLES.

Application filed March 2, 1927, Serial No. 171,944, and in Great Britain October 29, 1925.

This invention relates to improvements in the apparatus for automatically flanging and seaming sheet-metal receptacles in which both the flanging and seaming operations are 5 performed in rapid succession, for example the attachment of the end or ends, or base or cover, to sheet-metal drums of cylindrical and other regular section.

The invention embodies a type of machine 10 having two headstocks or equivalents comprising axially alined plates or chucks between which the work is held and rotated and there acted upon by suitably shaped rollers or the like by which the flanging 15 and seaming operations are successively performed during such rotation, the flanging rollers also preferably acting to support the work at certain times. One of the headstocks may be stationary and the other mov- 20 able or slidable to and away from the first as known in this type of machine, the work being held between the headstocks by bringing the movable stock up toward the stationary one, and mechanism may be pro- 25 vided by which the flanging and seaming operations take place either at one end of the work or at both ends of same simulta- neously.

According to this invention the actuating 30 means for the various rollers for performing the operations of flanging, curling, and flattening the metal joint are independent of each other, the flanging roller or rollers and the work-supporting roller or rollers 35 which co-operate therewith in the flanging operation being located in the vertical axis of the machine and operated each by a separate cam on cam shafts on opposite sides of the axis.

40 Also the curling roller or rollers and the flattening roller or rollers is or are mounted respectively on opposite sides of the vertical axis of the machine and movable in inclined guides converging towards said axis, each of said rollers being operated by a separate cam and the cams being mounted on opposite sides of said axis.

By such construction an efficient balancing 50 of all the main operative parts of the machine is produced and the actuation of the various rollers facilitated.

Thus, co-operating flanging rollers, arranged in the central axis of the machine and carried by slides, are adapted to be 55 given reciprocating movements to bring them into and out of action each by a sepa-

rate cam and act first to simultaneously flange the outer edge of the receptacle body and further flange the already previously flanged edge of the head which has been inserted in the end of the body. The flanged body and head are then acted on by a curling roller to produce a double more or less circular seam from the flanged portions of the body and head and finally the curled joint is 60 flattened by another roller to complete the joint, it being understood that the curling and flattening rollers are in turn each operated by an independent cam. The said curling and flattening rollers are located one 65 at each side of the flanging rollers and mounted in slides so that they have movement into and out of operation in inclined paths converging towards the central axis 70 of the machine.

It should be stated that the terms "head" 75 a "closure disk" used herein are intended to include end, bottom, base or other part to be attached to the body or main member of the work.

The invention also comprises other features of construction, arrangement, and combinations of parts as set forth in appended claims and hereinafter fully described with reference to the accompanying 80 drawings in which:

Fig. 1 is a side elevation of the machine with certain rollers omitted for sake of clearness; Fig. 2 is an end elevation from the left of Fig. 1; Figs. 3 and 4 are respectively cross-sections on lines 3-3 and 4-4 of Fig. 1 looking in the direction of the arrows; Figs. 5 and 6 are detail views showing in side elevation and plan respectively, the method of mounting the curling and 85 flattening rollers; and Figs 7 and 8 are detail views of certain operating cams and associated levers for the rollers.

In said drawings 1 designates the main frame of the machine on which is mounted at 90 each end a head-stock 2 and 3 respectively. The head-stock 2 is stationary and the head- 95 stock 3 movable or adjustable longitudinally of the machine as hereinafter explained. Each headstock is provided with suitable bearings for a shaft 4, 5 which respectively carry a plate or chuck 6, 7 between which the drum or receptacle, to which a head is to be applied at one or both ends is held during 100 operation of the machine.

The machine is driven by a shaft 8 having 105 fast and loose pulleys 9, 10 and from said

shaft to the chuck shafts 4, 5 by means of chain and pulley transmission 11, 12, each chuck shaft being positively operated.

From the chuck shaft 4 a train of gears 5 13—17 drives in opposite directions two cam shafts 18 and 19 mounted in the base of the machine at opposite sides of the longitudinal axis from which the various rollers are operated and controlled as will be described 10 later. The drive of shaft 8 is taken up by a friction clutch 20 (see particularly Fig. 4) of any appropriate kind but shown as comprising a friction band 21 under control of a weighted hand-lever 22 through lever and 15 link connections 23, 24, 25. One arm of lever 22 has a pin 26 engageable by a notch 27 in a latch 28 which in turn is controlled through arm 29 rod 30 and starpiece 31 operated by a cam 32 in such a manner that at 20 the end of each operation of the machine the pin 26 is automatically released from the notch 27 and the weighted lever 22 thrown over to stop the machine. The cam 32 is driven by bevel-gear 33 from the cam-shaft 25 19 and the star-piece 31 is under action of a spring 34 to keep it up to the periphery of said cam.

As aforesaid the head-stock 2 at the end of the machine just under consideration is 30 fixed and with it are associated the flanging rollers 35, 36 mounted in the central axis of the machine, the latter of which acts to support the work, and the curling and flattening rollers 37 and 38, these two latter rollers 35 being positioned on opposite sides of the axis of the chucks and movable in inclined paths toward and away from said axis. Similar rollers are also associated with and carried by the movable or adjustable head-stock 3 40 at the other end of the machine and are movable with said head-stock. These rollers are given similar reference characters to the others for convenience of description. The said head-stock 3 is adjustable as a whole in guides 42 on the machine frame by means of a hand-wheel 39 and screw-shaft 40, the latter engaging a nut 41 under the head-stock in order to provide for work or drums of varying length, and in addition the chuck 7 45 together with the flanging, curling and flattening rollers are independently movable on the head-stock, for which purpose they are all carried in a separate slide or stock 43 mounted on rollers 44 to reduce friction and 50 under the control of a hand-lever 45 by means of toggle levers 46 so that said slide can be moved forwards and backwards when inserting the work between, and removing it from, the chucks 6 and 7.

Having thus described the main operative 60 elements of the machine, I will now proceed to describe the particular arrangement and operation of the flanging, curling, and flattening rollers. Taking first the flanging 65 rollers 35, 36, these are mounted to rotate in

heads 47, 48 respectively carried by rods 49, 50 each in a sleeve 51, 52 forming part of the respective head-stocks with which they are associated. The rods 49, 50 pertaining to said rollers are extended below the bed of the frame and are connected by double links 53, 54 to double-armed levers 55, 56 respectively. Each of these levers carries a roller 57, 58 which is acted on by a cam mounted one on each of the shafts 18, 19. Lever 55 of roller 35 is operated by cam 60 on shaft 19 and lever 56 of roller 36 is operated by cam 61 on shaft 18, these cams so controlling the movements of the rollers that the rollers 36 are raised to support the work and immediately after the rollers 35 are lowered to flange the edges of the drum and head simultaneously in conjunction with the rollers 36, these operations taking place, in the form under consideration, at both ends of the work 80 at the same time. The levers 55, 56 are under the action of springs 55^a, 56^a to keep the rollers 57, 58 thereon in contact with the cam surfaces. After the operations described the rollers 35 and 36 return to the normal or neutral position shown in the drawings.

The next operation is the initial double seaming of the flanged connection produced by rollers 35, 36, and this is effected by raising the curling rollers 37, of which there is one associated with each head-stock, into contact with the work. These rollers are each carried by a head 62 working in inclined guides 63 converging in a direction towards the axis of the work support or chucks of the machine (see Figs. 3 and 4). To the head 62 is connected a rod 64 attached at its lower end to a bell-crank 65, one arm of which is provided with a roller 66 which is acted on by a cam 67 carried by shaft 18. After the curled joint has been formed by said rollers 37 it is flattened by the rollers 38 mounted in a similar manner to the curling rollers at the opposite side of the central axis of the machine and operated by bell-cranks 68 and cams 69 on shaft 19. The timing of the cams 67 and 69 is such that (see Fig. 8) the flattening operation follows closely on the curling operation and when said two operations are performed both said rollers recede to normal position, all the rollers being then in the position shown in the drawings. The levers 65, 68 are interconnected by springs 70 in order to keep them in engagement with their respective cams.

It will be obvious as regards the movable head-stock and its associated chuck slide that the roller operating cams, levers, and link connections must all be arranged to slide in relation to the cam shafts to permit the adjustment and movement of the head-stock and slide for the purpose stated or other suitable means provided for this purpose.

In the operation of an embodiment of a machine as above described the work, such as a drum, or receptacle body with flanged disk closures engaged in the ends thereof and to be seamed together is placed between the chucks 6, 7 and the hand-lever 45 operated which, through the connections mentioned moves the chuck slide so that the chuck 7 carried thereby grips the drum. The weighted hand-lever 22 is now operated and the machine started, the first operation being that of flanging the body of the drum and the end or ends by means of the rollers 35 which are controlled or operated by separate cams. The cam shafts 18, 19 are directly coupled to the head-stock spindle by the train of gears 13, 17, which causes said cam shafts to make one operation to the movement of the chucks necessary to complete the operations. The rollers 36 are advanced to support the drum while the flanging rollers perform their function. The flanging and supporting rollers 35, 36 are now caused to recede and the double seaming or curling rollers 37 each actuated by separate cams are caused to advance to produce a semi-completed seam from the previously flanged joint, after which the flattening rollers 38 advance to complete the seam. The mechanism is then stopped automatically through the cam 32, which is adapted to make one revolution to a complete cycle of operations, and the drum is released by manipulating hand-lever 45 and removed.

The mechanism of the present invention is equally applicable to machines in which the axes of the chuck and of the work are either vertical or horizontal or possibly also inclined.

What I claim as my invention and desire to secure by Letters Patent of the United States is:—

1. In apparatus for securing closures to sheet-metal receptacle bodies, the combination of a pair of axially arranged and opposed chucks between which a receptacle body with a flanged closure disk in each end is held, a pair of rollers associated with said chucks adapted to support the receptacle and flange the disk flanges and ends of the receptacle laterally, said rollers being located to rotate on axes parallel with the axis of the chucks, cam shafts disposed at opposite sides of said axis, cams on said shafts to independently actuate said rollers to move the rollers to flanging position and after the flanging operation to return the rollers to initial position, and rollers brought successively into operative relation with the flanged portion of the receptacle and closure disks to curl said flanged portion and then flatten the same against the receptacle body to form and seam the closures to the receptacle body.

2. Apparatus for securing closures to

sheet-metal receptacle bodies as claimed in claim 1, wherein the rollers to curl and flatten the flanged portions of the receptacle ends and closure flanges are disposed at opposite sides of the axis of the chucks and movable in inclined paths converging toward said axis, cam shafts arranged at opposite sides of said axis, and cams on said shafts to independently actuate each of said rollers to effect the curling and flattening of the flanged portions of the receptacle and closures in successive sequence.

3. In apparatus for securing closures to sheet-metal receptacle bodies as claimed in claim 1, a slide movable longitudinally of the apparatus and carrying one of said chucks with the associated flanging, curling and flattening rollers, and means for controlling the position of said slide comprising toggle mechanism and a hand lever connected thereto for actuating the same.

4. Apparatus for securing closures to sheet-metal receptacle bodies as claimed in claim 1, wherein the rollers to curl and flatten the flanged portions of the receptacle ends and closure flanges are disposed at opposite sides of the axis of the chucks and movable in inclined paths converging toward said axis, cam shafts arranged at opposite sides of said axis, cams on said shafts to independently actuate each of said rollers to effect the curling and flattening of the flanged portions of the receptacle and closures in successive sequence, a slide movable longitudinally of the apparatus and carrying one of said chucks with the associated flanging, curling and flattening rollers, and means for controlling the position of said slide comprising toggle mechanism and a hand-lever connected thereto for actuating the same.

5. In apparatus for securing closures to sheet-metal receptacle bodies, the combination of revolving chucks between which a receptacle with a flanged closure in each end is held, head-stocks carrying said chucks one of which is movable axially relative to the other, rollers associated with said chucks adapted to support the receptacle body and flange the ends of the body and flange of the closure disks laterally, said rollers being movable in a direction toward and away from the axis of the chucks, rollers to curl the flange portions of the receptacle and closures into a seam and flatten the same, said rollers being disposed at opposite sides of the axis of the chucks, cam shafts mounted at opposite sides of said axis, and cams on said shafts adapted to independently actuate the flanging rollers to effect the flanging operation and permit the return of said rollers to initial position, and actuate the curling and flattening rollers to effect the forming and flattening of the seam in successive sequence.

6. In apparatus for securing closures to sheet-metal receptacle bodies as claimed in

claim 5, means to adjust the adjustable head-stock carrying the one chuck, and wherein said head-stock also carries the flanging, curling and flattening rollers associated with the chuck carried thereby, and means to adjust said chuck and rollers independently of the head-stock.

7. In apparatus for securing closures to sheet-metal receptacle bodies, the combination of revolving chucks between which a receptacle body with a flanged closure disk in each end is held, rollers associated with said chucks adapted to support the receptacle and flange the ends and flanges of the closures laterally, and then successively curl the flanged portion of the receptacle and closure disks and flatten the curled flanged portion, said supporting and flanging rollers being arranged to rotate on axes parallel with and have movement in a direction toward and away from the axis of the chucks, cam shafts disposed at opposite sides of said axis, cams on said shafts to independently actuate all of the rollers, a driving shaft, chain gearing to positively drive the chucks from said shaft, clutch mechanism for controlling the connection of said chain gear with the drive shaft, and a train of gearing for driving the cam shafts from one of the chucks.

8. Apparatus for securing closures to sheet-metal receptacle bodies as claimed in claim 7, wherein the curling and flattening rollers are disposed at opposite sides of the axis of the receptacle supporting chucks and movable in inclined paths converging toward said axis.

9. In apparatus for securing closure disks to sheet-metal receptacle bodies, the combination of revolving chucks between which a receptacle with flanged closure disks engaged in the ends is held, movable and stationary head-stocks, chucks rotatably carried by the respective head-stocks, rollers associated with said chucks adapted to support the work and flange the ends of the receptacle with the closure flanges laterally, then successively curl the flanged portions

of the receptacle and closure disks and flatten the curled portions, the flanging and supporting rollers being located to rotate on an axis parallel with and have movement in a direction toward and away from the axis of the chucks, and the curling and flattening rollers being disposed at opposite sides of the axis of the chucks and movable in inclined paths converging toward said axis, cam shafts rotatable on axes parallel with the axis of the chucks and arranged at opposite sides thereof, cams on said shafts to independently actuate all of the rollers, means for adjusting the movable head-stock with the chuck and associated rollers longitudinally of the apparatus as a unit, means for adjusting said chuck and rollers independently in relation to said head-stock, a driving shaft, chain gearing to positively drive the chucks from said shaft, clutch mechanism for connecting the chain gearing with the drive shaft, manually operated means for controlling said clutch to connect the chain gearing with the shaft, means for automatically releasing said clutch mechanism upon each revolution of the chucks, and a train of gearing to drive the cam shafts from one of the chucks.

10. In apparatus for securing closures to sheet metal receptacle bodies, rotatable chucks for supporting a receptacle body with a flanged disk in the end, a pair of rollers rotatable on axes parallel with the axis of the chucks and movable in a direction toward and away from said axis and adapted to flange the end of the receptacle and closure flange laterally, and a pair of rollers rotatable on axes parallel with the axis of the chucks and movable toward and away from the chucks in inclined paths converging toward the axis of the chucks and adapted to operate on the flanged portion of the receptacle end and closure flange to curl said flanged portion and then flatten the same.

In witness whereof I have signed this specification.

CHARLES JOSEPH RHODES.
